UNITED STATES PATENT OFFICE.

SWAN NILS TEVANDER, OF MAYWOOD, ILLINOIS.

CAP FOR CANS MADE OF METAL OR OTHER MATERIAL.

Application filed August 20, 1920. Serial No. 404,883.

To all whom it may concern:

Be it known that I, SWAN NILS TEVANDER, a citizen of the United States, a resident of Maywood, in the county of Cook and State 5 of Illinois, have invented a new and useful Cap for Cans made of Metal or Other Material, of which the following is a specification.

My invention relates to covers for cans of 10 various types wherein the cap is sealed to the can top head by means of crimping the material of the cap into a frictional engagement with the body of the can. The object of the invention is to increase the efficiency 15 of the fastening of the cap to the can and provide a better form for the cap and the can opening.

The invention is set forth in the claims.

Reference will be had to the accompanying drawing in which Figure 1 is a front elevation of a can with my cap secured thereto.

Figure 2 is an enlarged detail sectional view showing the fastening of the cap to the 25 can top or head.

Figure 3 is a plan view.

Figure 4 is an enlarged sectional elevation of the head of the can prepared to receive my cap.

Figure 5 is a detail through the body of the cap when shaped in form to be fixed to the can.

Figure 6 is an enlarged detail showing a slightly different arrangement of the lining 35 material for the cap.

Figure 7 shows a detail of a modified form of the lining or sealing material for the cap.

In the drawing 1 indicates the body of the can made in any ordinary way of making 40 can bodies. The head or open end of this can is curled over into a roll as indicated by 2. This curling or beading is performed in the well known manner of tools used for that purpose. 3 indicates my can top which is 45 prepared in form as shown in Figure 5. This top is prepared with raised rim 4 having a peculiar shaped skirt or flange 5 which extends downward in the form of the outwardly concave corrugation 6 and the reverse corrugation 7 here shown in full lines 50 as having only two corrugations. However, when desired I may continue this flange or skirt giving it greater depth as indicated by 8 in dotted lines at the right side of Figure 5.

I prefer to line the inside of my cap with some desirable gasket material or packing material such as paper, wood pulp, composition, etc., and this may cover the entire area of the can cap as indicated by 9 in Figure 6, or it may extend only over the marginal area as indicated at 10 in Figure 2. In some instances this material may be omitted altogether, depending on the character of the contents to be carried by the can.

Neither paper nor other sheet material need be used for lining the cap, any suitable slightly compressible coating may be applied to the interior of the cap flange, as indicated at 11, Fig. 7.

The cans with which this cap is to be used may be made of any suitable material such as tin, paper, composition, etc. When the can body is made ready to receive the cap its 75 sides have the appearance indicated in Figure 4, or if desired they may be prepared with a slight indentation as is shown at 12, Fig. 6.

After the can has been supplied with its 80 contents the cap is placed over it as indicated in dotted lines in Figure 4 and is large enough to pass over freely without any forcing. Then with a special tool the skirt or flange of the cap on the outside of the can 85 head is crimped by vertical pressure applied on the top of the edge or rim 4 and the bottom of the skirt or flange 7, causing the corrugations to bend up into the form shown by the ribs 13 in Figures 2 and 6. In this 90° crimping action the tool simply draws up the skirt or flange of the cap and causes the metal to flow out in horizontal lines in both directions and in the case of a tin can or a paper can the force of this movement is sufficient to cause a slight indentation in the upper portion of a primarily cylindrical can wall as indicated at 12. The tools which perform this crimping are such that they of themselves do not directly produce this indentation 12 and the amount of it is controlled by the relative resistance or strength of the head of the can as compared to the moments between in the corrugated flange of the cap itself. Thus there takes place a 100 give and take of the parts which insures a tight joint between the can head and the cap without danger of any disruptive strains either in the cap itself or in the can head or body.

The indentation 12 is shown exaggerated in the drawings and in normal practice does not amount to a sufficient depth to prevent the cap from being pried off from the can 5 top with only a slight swelling or spring of the skirt or flange of the cap so that the cap top may be removed without disrupting either the material of the cap itself or the can and at the same time the seal of the cap 10 on the can is amply strong for holding the cover down for any normal service such as for canned goods of all sorts, including vegetables, meats, fish, etc.

A cap of this form is readily removed and 15 replaced, so that the open can may be set upon a table for use and the cover can be readily replaced, if desired, forming again a satisfactory closure when the can is to be used further.

20 This sort of a cap may be used for a wide variety of purposes besides the normal fruit and meat canning purposes, for instance it may be used for varnish and paint cans, syrup can and the cap be used as the service 25 cap in place of an ordinary cork as heretofore provided for a wide range of uses.

The expense of preparing this type of cap and fastening the same to the can is not greater than that now generally incurred 30 for what is termed "sanitary cans" and at the same time it provides for a serving container which is a great desideratum.

The body of the cap is normally below the end margin of the can which it closes and 35 has an upwardly extending marginal cylindrical wall 14 which fits against and stiffens the marginal portion of the can wall, whereby both cap and can strongly resist distortion or other injury, permitting the 40 use of unusually light material.

The can itself as made by the manufacturers is shipped to the packers with the cans and covers separate and the packer after filling the can with its contents places the 45 covers and does the sealing.

The cans heretofore used of the open top type have thin narrow flanges at the open ends of the can and these cans being shipped and handled sometimes rather carelessly this 50 thin flange at the top is often damaged and the packer does not notice the damage until after the can has been filled and the contents destroyed by leaks which are discovered

too late to save the contents of the can or the can itself. With my can the beaded end of the open end of the can is less easily damaged by handling and even though indentations may be caused by accident these will either be so slight as to not affect the proper sealing of the can or will be so marked as to be noticed by the packer before the can is supplied with its contents. The method of applying my cap and sealing the same to the can is such that considerable distortion may have taken place in the shape of the open end of the can and this distortion will be corrected by the tools that actually seal the can and the cap together. Thus a large saving will be had by the packer who uses my cap as compared with the use of the old style 70 end.

Further the cap when it is sealed upon the can, owing to the inset location of the head 3 of the cap and the stiffening flanges on the cap and the reinforcing of the can top end in the cap makes a stiffer head to resist damage in shipping the canned goods than is the other type of a cap fastening heretofore generally used.

What I claim is:

1. The combination with an open receptacle having an externally cylindrical upper portion, of a pliable metal cap having a marginal down-turned flange provided with an annular open corrugation with its inner 85 bend closely fitting said portion and permanently decreasing in internal diameter and gripping said portion more firmly when compressed vertically.

2. The method of sealing an open receptacle having a plain cylindrical neck which consists in placing upon the receptacle a cap having a pliable pendant marginal flange provided with an annular corrugation closely fitting the neck and compressing the corrugation vertically forcing and permanently holding it against the neck, regardless of recoil.

Signed at Chicago, in the county of Cook and State of Illinois, this 2nd day of 100 August, 1920.

SWAN NILS TEVANDER.
